VAPOR GENERATOR

George D. Ebbets, Kenilworth, N. J., assignor to
The Babcock & Wilcox Company, Newark, N. J.,
a corporation of New Jersey

Application September 9, 1938, Serial No. 229,074

5 Claims. (Cl. 122—302)

This invention relates to water tube steam boilers, and more particularly to bent tube boilers of the multiple drum type.

An object of the invention is to provide a bent tube boiler which operates at high efficiency.

More specifically, it is an object of the invention to provide a boiler with an economizer which can be added to an installation without necessitating any substantial change in the boiler setting or any additional economizer casing.

Other objects of the invention will appear as the accompanying description proceeds.

The invention will be described with reference to the accompanying drawings in which preferred embodiments of the invention are shown.

In the drawings:

Fig. 1 is a vertical side section of the 4-drum Stirling boiler;

Fig. 2 is a vertical section of the rear bank of a boiler, and showing the relationship of the economizer to the boiler tubes;

Fig. 3 is a detail of a modified embodiment of the invention including the arrangement of the upper portion of the economizer with reference to the rear drum;

Fig. 4 is a view similar to Fig. 3, but showing an additional embodiment of the invention;

Fig. 5 is a part of a horizontal section on the line 5—5 of Fig. 1;

Fig. 6 is a diagrammatic view in the nature of a transverse section through a rear bank of tubes arranged in accordance with the invention;

Fig. 7 is a view similar to Fig. 6 but showing a different arrangement of the economizer tubes in relation to the boiler tubes; and

Fig. 8 is a partial transverse section through a rear bank of tubes of a modification similar to that shown in Fig. 2, showing means for increasing the heat transfer rates.

Referring to Fig. 1 of the drawings, the front upper drum 10 is connected to the lower drum 12 by a bank of steam generating tubes 14 which extend over the furnace chamber 16. These two drums are also directly connected by tubes 18 which form a part of the middle bank of tubes 19.

Furnace gases passing from the furnace chamber 16 over the tubes 14 must pass around the upper end of the baffle 20 which extends between the two front rows of tubes 18, as shown in the drawings. Thence, the gases pass downwardly in a second gas pass between the baffle 20 and a rearward baffle 22 supported by some of the tubes 24 which directly connect the drum 12 with the middle upper drum 26.

After passing from the second gas pass around the lower end of the baffle 22, furnace gases pass through a third gas pass in which there is a rear bank of boiler tubes. This bank of tubes includes the tubes 28 which directly connect the drums 12 and 26 and other tubes 30 which di-

rectly connect the drum 12 with the rearmost upper drum, or the steam offtake drum 34. From the third gas pass the gases proceed upwardly past a damper 36, to a flue.

5 A baffle 21 extending from the setting wall 112 across the tubes of the rear bank causes the furnace gases to move across those tubes to the space forwardly of that bank and then move again across the tubes as they pass out of the boiler setting.

Excessive bypassing of the gases around the economizer (to be later described) in the rear bank is prevented by the baffle 23 which extends from the economizer upwardly toward the baffle 25. The baffle 23, however, stops short of the baffle 25 to provide a vent 27 for the gas pocket between the baffles 22 and 25.

The tubes 28 and 30 of the rear bank may be spaced as indicated in Fig. 8 of the drawings, in 20 which the rows of tubes A and B are more closely spaced than the rows B and C. Similarly, the rows C and D are more closely spaced than D and E, etc. Between the more widely spaced rows B, C, D, and E, there are rows F and G of economizer tubes 40. These tubes are connected at their lower ends to the inlet header 42 which receives feed water from a suitable source. These tubes extend upwardly from the header 42 with their main portions in parallelism with adjacent boiler tubes of the rows A, B, C, and D, and at a 25 position near the drum 34 the economizer tubes are bent rearwardly away from the rear bank of tubes for connection to the upper economizer header 44. From that header, the heated feed water is discharged through the connections 46 into the drum 34.

When the boiler tubes of the rear bank, and the economizer tubes are arranged as indicated in Fig. 8 of the drawings, the spaces between 40 some of the rows of boiler tubes, such as the rows A and B, on the one hand, and C and D, on the other hand, may be closed off by the heat resistant elements 50 at one or more positions. Such positions are indicated at 52, 54, 56, and 45 58 in Fig. 2 of the drawings. These refractory elements operate to increase the velocity of the furnace gases in contact with parts of the economizer tubes and thereby increase the rates of heat transfer to the feed water in the economizer. Additional gas confining baffles 53 and 57 (Fig. 2) are used in conjunction with the baffle elements 50 in the Fig. 2 modification, and in the Fig. 1 modification the filter baffles 55 (see also Fig. 7) are used above the cross baffle 21.

55 Fig. 6 of the drawings shows a modified arrangement of tubes for the rear bank, the rows of the economizer tubes being indicated at 60—64, inclusive, while the rows of boiler tubes are indicated at 65—69, inclusive.

An arrangement of the tubes of the rear bank

of the Fig. 1 modification is indicated in Fig. 7 of the drawings, wherein the rows of economizer tubes R, S, and T are arranged, respectively, between the rows A and B, the rows C and D, and the rows E and L of the boiler tubes.

In the modification indicated in Fig. 3 of the drawings, the economizer tubes 70 are connected to the economizer outlet header 72 which, in turn, is connected to the drum 74 by the tubes 76. The header 72 may also be vented to the steam space of the drum 74 by tubular connections 78 and 80 connected by the valve 82.

In the embodiment indicated in Fig. 4 of the drawings the economizer tubes 84-89, inclusive, are directly connected to the drum 90 at positions on opposite sides of the boiler tubes 92 of the rear bank.

Feed water, in passing upwardly from the economizer inlet header 42 through the economizer tubes, is raised in temperature toward the saturation temperature corresponding to the pressure under which the boiler is operating. In the boiler tubes 30 adjacent the economizer tubes the temperature of the water is always below the saturation temperature because the water delivered by the economizer to the drum 34 is below saturation temperature. In this drum the incoming water from the economizer mixes with boiler water at saturation temperature, and the resulting mixture is therefore below the saturation temperature.

The illustrative boiler also includes the water circulators 100 directly connecting the drums 10 and 26, and the steam circulators 102 directly connecting the same drums. Steam is transmitted from the steam space of the drum 26 directly to the steam space of the drum 34 through the steam circulators 104 and 106, and the steam passes from the drum 34 through the offtake connection 108 to a point of use.

The front and rear walls of the boiler setting indicated in Fig. 1 of the drawings are shown respectively at 110 and 112, the roof portions of the setting being defined and supported by the circulators 102 and 106. These roof portions are shown respectively at 114 and 116.

I claim:

1. In a water tube steam boiler, means forming a submerged water chamber, upper drums, front and rear banks of tubes connecting the water chamber to the upper drums, an economizer including upright tubes in rows positioned between the rows of boiler tubes of said rear bank of tubes and extending in parallelism therewith, said economizer tubes having their upper and outlet ends joined to a separate header or drum in communication with the rear upper drum, the lower ends of the economizer tubes being joined to a separate lower header or drum, and means for supplying feed water to the last mentioned separate header or drum, there being normally no direct communication between said water drum and the lower ends of the economizer tubes.

2. In a water tube steam boiler, upper drums, means forming a submerged water chamber, separated front and rear banks of boiler tubes directly connecting said water chamber with the upper drums, said tubes being arranged in rows running transversely of the axes of said drums, an economizer including spaced tubes arranged in rows between some of the rows of tubes in the rear bank, means for supplying feed water to

the lower ends of the economizer tubes, means connecting the upper ends of the economizer tubes for discharge into the water space of the rear upper drum, and rows of refractory ele-

5 ments supported by the tubes of the rear bank and disposed between said tubes to increase the velocity of the furnace gases over the economizer tubes and consequently the rate of heat transfer from the furnace gases to the feed water in the economizer tubes, said refractory elements being arranged transversely of gas flow and closing the spaces between boiler tubes of the rear bank.

3. In a water tube steam boiler, upper and lower drums, two sets of substantially parallel tubes arranged as a bank of tubes in a single longitudinal gas pass between the drums with the tubes of one set directly connecting the drums and providing a part of the boiler circulation circuit, separate upper and lower headers 15 or drums for the remaining set of tubes, separated baffle members secured to some of the tubes and extending to adjacent tubes in said gas pass, said baffle members being disposed transversely of gas flow and arranged to close the spaces between the boiler tubes, means for supplying feed water to the lower header or drum for tubes of the second set, and means connecting the upper header or drum for the second set of tubes with the upper drum for the first set of tubes for the 20 delivery of heated feed water to the last mentioned drum.

4. In a water tube steam boiler, means forming a submerged water chamber, upper drums, front and rear banks of tubes connecting the water chamber to the upper drums, an economizer including rows of upright tubes positioned between the rows of boiler tubes of said rear bank of tubes and extending in parallelism therewith, said economizer tubes having their outlet ends 35 communicating with the rear drum, and separate refractory elements between adjacent boiler tubes of the rear bank and distributed across the gas flow to increase the velocity of the furnace gases over the economizer tubes, said refractory elements substantially closing spaces between the boiler tubes of the rear bank.

5. In a water tube steam boiler, upper drums, means forming a submerged water chamber, separated front and rear banks of boiler tubes directly connecting said water chamber with the upper drums, said tubes being arranged in rows running transversely of the axes of said drums, an economizer including spaced tubes arranged in rows between some of the rows of boiler tubes 55 in the rear bank, a lower header to which the economizer tubes are connected, means for supplying feed water to the economizer tubes, an upper header to which the upper ends of the economizer tubes are connected, means connecting the upper header to the water space of the rear upper drum, and rows of spaced refractory elements supported by tubes of the rear bank and distributed across the gas flow to increase the velocity of the furnace gases over the economizer tubes and consequently the rate of heat transfer 60 from the furnace gases to the feed water in the economizer tubes, said refractory elements closing spaces between adjacent boiler tubes of the rear bank and being arranged transversely of gas flow.

GEORGE D. EBBETS.
